(57) **CLAIM**

The ornamental design for a pet harness, as shown and described.

DESCRIPTION

FIG. 1 is a top view of a pet harness, with folds in a closed position, showing my new design;

FIG. 2 is a front side view of the pet harness of FIG. 1;

FIG. 3 is a back side view of the pet harness of FIG. 1;

FIG. 4 is a right side view of the pet harness of FIG. 1;

FIG. 5 is a left side view of the pet harness of FIG. 1;

FIG. 6 is a bottom view of the pet harness of FIG. 1;

FIG. 7 is a perspective view of the pet harness of FIG. 1, with folds in a closed position;

FIG. 8 is a top view of the pet harness of FIG. 1, with folds in an open position, to show a reel housing and a strap, which are not visible in FIG. 1;

FIG. 9 is a front side view of the pet harness of FIG. 8, with folds in an open position;

FIG. 10 is a back side view of the pet harness of FIG. 8, with folds in an open position;

FIG. 11 is a right side view of the pet harness of FIG. 8, with folds in an open position;

FIG. 12 is a left side view of the pet harness of FIG. 8, with folds in an open position;

FIG. 13 is a bottom view of the pet harness of FIG. 8, which is not visible in FIG. 8;

FIG. 14 is a perspective view of the pet harness of FIG. 8, with folds in an open position; and,

FIG. 15 is a perspective view of the pet harness of FIG. 1, shown in use.

The broken line showing of stitching is part of the claimed design. The broken line showing of a dog and human hand in FIG. 11 is illustrative of environment only and is not claimed.

1 Claim, 11 Drawing Sheets
